UNITED STATES PATENT OFFICE.

AUGUST DE TREY, OF PHILADELPHIA, PENNSYLVANIA.

INHALER.

No. 802,839.

Specification of Letters Patent.

Patented Oct. 17, 1905.

Application filed April 17, 1905. Serial No. 255,963.

To all whom it may concern:

Be it known that I, AUGUST DE TREY, a citizen of the Republic of Switzerland, residing in Philadelphia, Pennsylvania, have invented 5 certain Improvements in Inhalers, of which the following is a specification.

One object of my invention is to provide an inhaler with improved means for breaking an anesthetic-containing and frangible capsule 10 after the latter has been properly inserted in the inhaler, it being further desired to provide means for properly directing and distributing the liquid delivered from said capsule upon absorbent material suitably placed 15 within the inhaler. These objects I attain as hereinafter set forth, reference being had to the accompanying drawings, in which—

Figure 1 is a perspective view of my improved inhaler, and Fig. 2 is a sectional elevation showing the interior construction of the inhaler illustrated in Fig. 1.

In the above drawings, A is a metal tube made in two portions *a* and *a'* at right angles to each other. To one end of the part *a* is 25 connected a face-piece B, consisting of a pneumatic rubber pad *b* and a supporting-cone *b'* therefor. The opposite end of the said part *a* is provided with a tube *c*, fitting within it and having a cap C, there being one or more 30 openings in said tube for regulating the supply of air.

Projecting into the tubular part *a* in the line of the right-angled portion *a'* is a tubular guide *a''*, and there is in addition a tube *c'*, 35 carried by the tube *c*, which may in one position of this latter form a continuation of the guideway *a''*. The lower end of the tubular part *a'* is provided with an enlarged neck *a'''* for the reception of an air-bag D, while there 40 is within said portion *a'* a removable frame *d*, formed of spirally-wound wire, upon which is carried a body of absorbent material *d'*, such as cotton or gauze. Forming part of 45 the frame *d* is a removable cap *a''*, having an opening covered with a piece of gauze *a'''*.

Extending across the tubular portion *a'* above the frame *d* is a deflector E, preferably consisting of two plane portions connected along a common edge and placed to one side 50 of the center line of the guideway formed by the tubes *a''* and *c'*. Between the end of the tube *c'* and the adjacent edge of the deflector E are two pins *e* and *e'*, forming stops, although, if desired, but one of these, as *e*, may 55 be used. Said stops extend across the tubu-

lar portion *a'* in lines preferably parallel with the surface of the piece E.

When it is desired to provide the inhaler with anesthetic, the capsule, which is frangible and usually of the form shown in dotted 60 lines at F, is inserted through the guideway *a''*, so that its elongated end strikes the inclined surface of the deflector E. If the capsule be forced farther into the inhaler, said end engages the stop *e*, so that it is broken, 65 and the liquid anesthetic is directed by the deflector to the tubular body *b'* of absorbent material. It will be seen that this directing of the liquid is due to the shape of the piece E, which by deflecting it toward the sides of 70 the tubular portion *a'* prevents its falling straight through the open central portion of the frame *d*. As will be understood by those skilled in the art, the amount of air entering the inhaler is regulated by the operation of 75 the cap C in the well-known manner.

I claim as my invention—

1. An inhaler having a guideway for an anesthetic-containing frangible capsule, and means for automatically breaking said capsule within the inhaler when said capsule is forced into the guideway, substantially as described. 80

2. The combination in an inhaler of a tubular guideway, a piece within the inhaler inclined to the line of the guideway and placed to engage and break the end of an anesthetic-containing frangible capsule forced into the 85 guideway, substantially as described.

3. The combination in an inhaler of a tube 90 containing a body of absorbent material and having an opening, and a deflector having a surface inclined to the line of said opening and placed to engage the end of an anesthetic-containing frangible capsule forced into the 95 opening, said deflector also directing liquid from said capsule to the absorbent material, substantially as described.

4. The combination in an inhaler of a tubular guideway, a piece having its surface inclined to the line of said guideway, and a stop adjacent to said surface, said parts being arranged to engage and break the end of a frangible capsule forced into said guideway, 100 substantially as described. 105

5. The combination in an inhaler of a tubular guideway, a piece having its surface inclined to the line of said guideway, and a stop adjacent to said surface, said parts being arranged to engage and break the end of a 110

frangible capsule forced into said guideway, with a body of absorbent material placed to receive liquid delivered from a capsule in the guideway, substantially as described.

5 6. The combination in an inhaler of a tubular structure having two portions substantially at right angles to each other, a tubular body of absorbent material in one of said portions, a tubular guideway carried by the other portion, and a piece inclined to the line of said guideway and placed to direct fluid from a capsule in the guideway upon said absorbent

material, with a stop adjacent to said piece placed to coact therewith to break the point of a frangible capsule forced into said guideway, substantially as described. 15

In testimony whereof I have signed my name to this specification in the presence of two subscribing witnesses.

AUGUST DE TREY
